UNITED STATES PATENT OFFICE.

FREDERICK B. DUNCAN, OF MADISON, WISCONSIN, ASSIGNOR TO NORTHERN ELECTRICAL MANUFACTURING COMPANY, OF MADISON, WISCONSIN, A CORPORATION OF WISCONSIN.

DEVICE FOR CONTROLLING MOTORS.

No. 800,611.

Specification of Letters Patent.

Patented Sept. 26, 1905.

Application filed December 30, 1901. Serial No. 87,656.

To all whom it may concern:

Be it known that I, FREDERICK B. DUNCAN, a subject of the King of Great Britain, residing at Madison, in the county of Dane and State of 5 Wisconsin, have invented a certain new and useful Improvement in Devices for Controlling Motors, of which the following is a specification.

My invention relates to devices for controlling motors, and has for its object to provide a new and improved device and system of this description.

My invention is illustrated in the accompanying drawings, wherein—

15 Figure 1 is a diagrammatic view of a system embodying my invention. Fig. 2 is a diagrammatic view showing the connections and associated parts of one motor and controlling mechanism. Fig. 3 is a view showing the 20 reversing-switch.

Like letters refer to like parts throughout the several figures.

In Fig. 1 I have illustrated a series of devices or machines involving a system embodying my invention. For purposes of illustration I have taken a machine-shop containing lathes, planers, and the like. Each machine A is operated by a separate motor, the rheostats or controllers T for which are located on 25 a switchboard B at some convenient part of the shop and out of reach of the operator of the lathe or other machine. The controllers are operated by means of push-buttons A' A² A³ A⁴, &c., located on the lathes, there being 30 suitable connections between the push-buttons and motor and the controller on the switchboard.

In Fig. 2 I have illustrated one motor and the controlling mechanism therefor. In this 40 construction the usual armature resistance is provided, said resistance being controlled by the arm C. This arm moves over suitable contacts connected with the armature resistance R and the field resistance R' and is provided 45 with the retracting-spring C'. Said arm is also provided with a ratchet segment or rack having teeth C², adapted to be engaged by the pawl or engaging part D' on the core of the magnet or solenoid D. This engaging part 50 is attached to a piece which is pivotally connected to the core of said magnet so that it may have a slight side movement, and said piece is also provided with the inclined projection D², which engages a suitable pin or 55 stop, so that when no current is flowing through

the solenoid the engaging part will be out of engagement with the teeth. The solenoid D is connected by conductor D³ with the contact D⁴ of the reversing-switch E and also with the switch or push-button A² by conductor D⁵. 60 Said push-button is connected to the negative line of the system by conductor X. A holding-magnet F is associated with the arm C, and its armature is provided with an engaging piece F', which engages said teeth when 65 the magnet is energized, there being a retracting-spring F², which pulls the armature away from the magnet when it is demagnetized, so as to release the arm. The engaging piece F' is connected by a flexible link 70 with the core of the solenoid or magnet G, adapted when actuated to permit the arm of the controller to move, so as to slow down the motor. The magnet F is connected with the arm C by conductor F³ and with the positive 75 line by conductor F⁴. A short-circuiting conductor F⁵ passes around said magnet and through the push-button A⁴, so that when said push-button is closed the magnet will be short-circuited. The core of the solenoid G is provided 80 with an engaging arm G', pivoted thereto and also pivoted at G². This arm engages the teeth C² when the solenoid is energized, and the retracting-spring G³ withdraws it 85 from engagement when the solenoid is de-energized. This solenoid G is connected to the conductor D³, and hence the positive line of the system, by conductor G⁴ and with the push-button A³ by conductor G⁵. Said push-button is connected by conductor X with the 90 negative line of the system.

The reversing-switch E is provided with two sets of arms E' and E², which engage suitable contacts. This switch is adapted to be worked automatically and is provided with a toothed 95 disk E³, which is engaged by a hook E⁴, carried by a part pivotally connected to the core of the reversing solenoid or magnet I. When this magnet is energized, the reversing-switch is moved so as to reverse the currents in the 100 motor. Said solenoid is connected to the positive line by conductor I' and to the push-button A' by conductor I², said push-button being connected to the negative line by conductor X.

The positive line of the system is connected by conductor K with the contact K', (see Fig. 3,) and the armature of the motor is connected by conductors L with the contacts L' and L² of the switch. The negative line is con- 110

nected to contact L^3 of the switch, and the field-circuit M of the motor is connected to the contact M' .

The controlling device may be located on the machine or other device operated by the motor, or it may be located on a distant switch-board. In Fig. 1 the controllers of the several machines are placed on a single switch-board at a distant point, and hence are entirely beyond the control of the operator, who stands by the machine.

The use and operation of my invention are as follows: When it is desired to start the motor, the push-button A^2 is pressed. This completes the circuit through solenoid D , said circuit being traced as follows: from positive line Y to switch E , thence by conductor D^3 through solenoid D , thence by conductor D^5 to push-button A^2 , thence to conductor X , and thence back to the negative line. Solenoid D is then energized, lifting its core and moving the arm one notch. The arm is held in this position by the engaging piece F' on the armature of the magnet F , the circuit through said magnet being as follows: from positive line Y through switch E , conductor D^3 , arm C , conductor F^3 , magnet F , and conductor F^4 , thence through the field-magnet coils of the motor, thence back to contact M' of the switch, and thence to the negative line Z . To move the arm up another notch, the push-button is released, permitting the core to fall and is then again pressed, the operation hereinbefore set out being repeated. The movement of the arm cuts out the armature resistance R , so as to speed up the motor, and near the end of its movement cuts resistance R' into the field-circuit, thus further increasing the speed of the motor. It will thus be seen that the arm C may be held in any desired position, depending upon the number of times the push-button is pushed. If now it is desired to stop the motor, the push-button A^1 is pushed. This short-circuits the magnet F , the circuit instead of going through said magnet passing through conductor F^5 , through the push-button, and back to the field-coil M , the rest of the circuit being the same as before. When the magnet F is short-circuited, it becomes de-magnetized, and the spring F^2 moves the armature so that the engaging piece F' is withdrawn from the teeth, and the arm C is released, the spring then throwing said arm suddenly back to its initial or off position. The flexible link between the engaging piece F' and the core of solenoid G bends at the pivoted point and permits this movement of the engaging piece F' . If it is desired to slow down the motor gradually when it is going at any particular speed, the push-button A^3 is pushed. This completes the circuit through solenoid G , said circuit being as follows: from positive line Y through switch E , conductor D^3 , conductor G^4 , magnet G and conductor G^5 , through push-button A^3 , and thence through conductor

X and back to the negative line. The solenoid G is now energized and draws its core inwardly. The engaging piece F' is then moved out of engagement with the teeth C^2 , and the bent arm G' is thrust forward so as to engage said teeth. This lets the spring of arm C pull said arm back one tooth. If now the push-button is released, the parts take the position shown in Fig. 2, and if it is desired to move the arm backward farther the push-button is again pushed. It will thus be seen that the arm may be moved backward, so as to throw any desired resistance in the armature-circuit and slow down the motor to the desired speed. This is of the greatest importance in connection with such machines as lathes, for it is often necessary to slow down the speed when the work is in the lathe. If it is necessary to stop the motor to slow down the speed, a mark is left on the work by the tool. All this is avoided by means of my controlling device. The circuit through the armature is as follows: from positive line Y to contact K' of switch E , thence across said switch to contact D^4 , (see Fig. 3,) thence by conductor D^3 to arm C , thence through armature resistance, thence to contact S , (see Fig. 3,) thence to contact L' , thence through the armature, thence to contact L^2 , thence to contact L^3 , and back to the negative line Z . If it is desired to reverse the motor, the push-button A^1 is pushed. This completes the circuit through solenoid I , said circuit being as follows: from positive line Y through conductor I^1 to solenoid I , thence by conductor I^2 to push-button A^1 , and thence through conductor X back to the negative line. The solenoid I is thus energized and moves its core upwardly so as to rotate the switch a quarter of a turn, thus changing the arms which make contact with the contacts and reversing the current. The movement of this switch has no effect upon the operation of the other devices of the controller.

It will thus be seen that I have here a device for controlling the various machines in a shop at the machine, the controlling parts being located away from the machine so as to be out of the reach of the operator, and that the motor is started up or slowed down by a step-by-step process entirely independent of the operator and beyond his control, and that there is no way by which the machine can be started up or slowed down without going through this step-by-step process, thus preventing injury to the motor by the sudden change of resistance in the armature-circuit.

I claim—

1. The combination with a motor of a controlling-rheostat, a device for moving the rheostat by a step-by-step movement to cut out resistance, a holding device for holding the rheostat-arm, a releasing device for releasing the rheostat-arm by a step-by-step movement, so that it may be returned to its

initial position, and a connection between the movable parts associated with the holding-magnet and the releasing-magnet.

2. The combination with a device to be driven of a motor associated therewith, a rheostat at a distant point adapted to be connected in circuit with said motor, a controlling mechanism for the arm thereof, adapted to move said arm by a step-by-step movement in both directions, and push-buttons or switches at the machine for controlling the operation of said controlling mechanism.

3. The combination with a machine to be driven of an electric motor, a rheostat at a distant point, a step-by-step actuating-solenoid associated with the arm of said rheostat, and provided with a core adapted to be connected with and disconnected from the arm of the rheostat, a holding device associated with the rheostat-arm and adapted to engage it at a different point from that of the controlling rheostat-arm and a switch at the machine for controlling said solenoid, whereby resistance is cut out from the armature-circuit by a step-by-step process.

4. The combination with a machine to be driven of an electric motor, a rheostat at a distant point, a step-by-step actuating-solenoid associated with the arm of said rheostat, a switch at the machine for controlling said solenoid, a holding-magnet associated with said rheostat-arm and adapted to hold it in the position to which it is moved by the step-by-step actuating device, the actuating-solenoid and holding-magnet adapted to engage and disengage with the rheostat-arm successively during the operation of the device and a push-button at the machine for rendering said holding-magnet inoperative.

5. The combination with a machine to be driven of an electric motor, a rheostat or starting-box at a distant point, a step-by-step actuating-solenoid associated with the arm of said rheostat, a switch at the machine for controlling said solenoid, a holding-magnet associated with said rheostat-arm and adapted to hold it in the position to which it is moved by the step-by-step actuating device, a push-button at the machine for rendering said holding-magnet inoperative, a releasing-magnet associated with said arm and provided with attachments which release the arm by a step-by-step movement, and a controlling connection between the parts controlled by the releasing-

magnet and the holding-magnet and a switch at the machine for controlling said releasing-magnet.

6. The combination with a machine to be driven of an electric motor, a rheostat or starting-box at a distant point, a step-by-step actuating-solenoid associated with the arm of said rheostat, a switch at the machine for controlling said solenoid, a holding-magnet associated with said rheostat-arm and adapted to hold it in the position to which it is moved by the step-by-step actuating device, a push-button at the machine for rendering said holding-magnet inoperative, a releasing-magnet associated with said arm and provided with attachments which release the arm by a step-by-step movement, a switch at the machine for controlling said releasing-magnet, a reversing-switch for said motor at a distance from the machine, and a switch at the machine for automatically controlling it.

7. The combination with a lathe of an electric motor, a rheostat or starting-box therefor, having a contact-arm provided with a rack, a solenoid located near said rack, provided with a core having a pawl or ratchet adapted to engage the teeth of the rack so as to move said arm a predetermined amount each time the solenoid is energized, a holding-magnet associated with said rack and having an engaging device on its armature for holding the arm in the position to which it is moved, suitable switches or push-buttons on the lathe for controlling said magnet and solenoid, whereby a step-by-step movement of the starting-box arm is insured when the motor is being started.

8. The combination with a lathe of an electric motor, a starting-box therefor out of the reach of the lathe operator, a rack on the contact-arm of said starting-box, a solenoid located near said rack and provided with a core having a pawl adapted to engage said rack, a push-button or switch on the lathe in position to be conveniently controlled by the operator, whereby the starting-box arm is moved by a step-by-step motion when the push-button or switch is operated and a stop device adapted to engage the rack on the contact-arm when it is released by the ratchet associated with the said solenoid.
